UNITED STATES PATENT OFFICE

2,565,704

HATCH CONSTRUCTION

James S. Swann, Homewood, Ill., assignor to
 Standard Railway Equipment Manufacturing
 Company, Chicago, Ill., a corporation of Delaware

Application February 24, 1948, Serial No. 10,479

4 Claims. (Cl. 108—5.4)

1

This invention relates to the hatch construction of metal car roofs of the type wherein the hatchways are arranged in pairs, one on each side of the roof, and are defined by metal hatch frames that extend above the general level of the roof.

Usually a roof sheet conforming to the shape of the adjacent roof sheets extends between and is secured to the facing sides of the hatch frames. With this construction the ridge of the car roof continues longitudinally of the roof between the hatch frames, and as a consequence, water, cinders, dirt, etc. collect along the sides of the hatch frame adjacent the ridge of the car, greatly accelerating corrosion which is, of course, a detriment to any roof.

The principal object of the invention therefore is to provide a roof sheet between such hatch frames which is as self clearing as possible. Other objects are to provide for simplicity and cheapness of construction and compactness of design.

Other objects and advantages will appear in the following description thereof.

Referring now to the accompanying drawing forming part of this application and wherein like reference characters indicate like parts:

Figure 1 is a plan view of a portion of a metal car roof provided with a roof and hatch construction embodying my invention.

Figure 2 is a transverse section through a roof sheet adjacent the hatch frames and taken on the line 2—2 Figure 1.

Figure 3 is a longitudinal section through the roof sheet between the hatch frames on the line 3—3 of Figure 1.

Figure 4 is a section similar to Figure 3 but on line 4—4 of Figure 1.

Figure 5 is a fragmentary perspective view showing the roof sheet between the hatch frames and the associated parts partly in section and partly broken away.

In the drawings the invention is shown embodied in a railway car roof comprising roof sheets 1 that span from side plate 2 to side plate 2 of the car and have depending end or eave flanges 3 that overlap and are riveted or otherwise rigidly secured to the outer sides of the upstanding flanges 4 of the side plates.

The hatch frames are indicated at 5 and are usually of rectangular form and of sufficient depth to extend both above and below the roof sheets. The upper edges of said frames are usually bent outwardly as shown at 6 to provide strength, pleasing appearance, and form a seat for a hatch plug or cover, not shown. These hatch frames

2

5 are located in the roof directly above the ice or refrigerant bunkers and are supported in position by a pair of carlines 7 which extend from side to side of the car and are secured in any desired manner at their ends to angle brackets 8 which in turn are secured by rivets 9 or other acceptable means to side plates 2. Carlines 7 are spaced apart the width of the hatch frames and the adjacent sides of the hatch frames are secured 10 by welding or other acceptable means to said carlines, thereby providing adequate and rigid support therefor. Carlines 7 are of course inclined upwardly from the side plates to the ridge, and the roof sheets 1, on opposite sides of the 15 hatch frames rest upon and are supported along one edge by the lateral flange of said carline 7.

Between the hatch frames 5 and extending also between the carlines 7, is a rectangular roof sheet 10 which is bent transversely along a medial 20 line 11 from side to side of the sheet forming a transverse ridge and sloping downwardly on opposite sides thereof. The sides of this sheet 10 have upturned flanges 12 which are welded to the adjacent sides of the hatch frames. This roof 25 sheet 10 is also bent along a longitudinal line 13 which is coincident with the ridge 14 of the car roof and slopes upwardly from its juncture with ridge 14 to its juncture at joint 15 with ridge 11. Each end of the sheet 10 is provided with a laterally extending flange 16 which rests upon and is secured by welding or otherwise to the upper flange of carline 7.

The roof sheets 1 are provided with upstanding flanges 17, which flanges 17 and an adjacent strip 35 of roof sheets 1 approximating the width of flanges 16, are coped out as at 18, so as to permit flanges 16 and the abutting roof sheet 1 to occur in the same plane and be butt-welded together and to carlines 7, as at 19. (See Figures 3 and 4.) Flanges 17 are welded or secured to the sides of 40 hatch frames 5.

In the roof sheet 10, four diagonal valleys are formed, each extending from point 15, approximately in the center of the sheet, to a corner of the sheet. In other words, the two intersecting fold lines 11 and 13 divide the sheet 10 into four substantially equal quarters, each quarter being provided with a diagonal valley extending between two opposite corners thereof. This structure results in a ridge and valley roof sheet extending between the hatch frames and between the carlines 7, with all valleys sloping downwardly from an apex 15 to the corners of the sheet, and also the sheet sloping downwardly 55 away from the sides of the hatch frame. The

roof sheet is therefore almost self clearing of any cinders, dirt, or other undesirable foreign matter which might otherwise lodge in the corners between the sheet and side of hatch frame. Also a roof sheet of the described formation results in a very strong sheet resistant to forces imposed downwardly thereupon.

Having thus described my invention, what I claim and desire to secure by Letters Patent is:

1. In a railway car roof having a longitudinal ridge and a pair of spaced hatch frames embodied in said roof, a roof sheet located between said hatch frames and formed with a transverse ridge above the general level of the car roof, and a longitudinal ridge, said ridges intersecting at the approximate center of said sheet, said longitudinal ridge sloping downwardly on opposite sides of said transverse ridge to the plane of the ridge of the car roof on opposite sides of said roof sheet.

2. In a railway car roof having a longitudinal ridge and a pair of spaced hatch frames embodied in said roof, a roof sheet located between said hatch frames and formed with a transverse ridge above the general level of the car roof, and a longitudinal ridge in line with the ridge of the car roof, said ridges intersecting at the approximate center of said sheet, said longitudinal ridge sloping downwardly on opposite sides of said transverse ridge to the plane of the ridge of the car roof on opposite sides of said roof sheet, and a plurality of valleys formed in said roof sheet, each valley extending from the intersection of said ridge to a corner of said roof sheet.

5 section of said ridge to a corner of said roof sheet.

3. In a railway car roof having a longitudinal ridge and a pair of spaced hatch frames embodied in said roof, a roof sheet located between said hatch frames and formed with a transverse ridge above the general level of the car roof, and a longitudinal ridge in line with the ridge of the car roof, said ridges intersecting at the approximate center of said sheet, and a plurality of valleys formed in said roof sheet, each valley extending from the intersection of said ridge to a corner of said roof sheet.

4. A roof sheet for a railway car roof, said roof sheet formed with a transverse ridge and a longitudinal ridge, said ridges intersecting at the approximate center of said sheet, said longitudinal ridge sloping downwardly on opposite sides of said transverse ridge, and a plurality of valleys formed in said roof sheet, each valley extending from the intersection of said ridge to a corner of said roof sheet.

JAMES S. SWANN.
